(57) **CLAIM**

The ornamental design for a cup drying stander, as shown and described.

DESCRIPTION

FIG. 1 is a front perspective view of a cup drying stander, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is a perspective view of the cup drying stander of FIG. 1 wherein a pole of the cup drying stander is separated from a base of the cup drying stander.

FIG. 9 is a perspective view of the cup drying stander folded up; and,

FIG. 10 is a perspective view in USE stage thereof, showing a cup hanging on the cup drying stander of FIG. 1.

The broken lines in the drawings depict environmental structure and boundaries and form no part of the claimed design.
